UNITED STATES PATENT OFFICE.

OSCAR P. WALBERG, OF KIMBALL, MINNESOTA.

DESIGN FOR AN INKSTAND.

46,520.

Specification for Design.

Patented Oct. 6, 1914.

Application filed June 22, 1914. Serial No. 846,693. Term of patent 7 years.

To all whom it may concern:

Be it known that I, OSCAR P. WALBERG, a citizen of the United States, residing at Kimball, in the county of Stearns and State of Minnesota, have invented a new, original, and ornamental Design for Inkstands, of which the following is a specification, reference being had to the accompanying drawing, forming part thereof.

The figure is a perspective view of an ink stand, showing my new design.

I claim:

The ornamental design for an ink stand, as shown.

OSCAR P. WALBERG.

Witnesses:

L. L. OLSON,
A. H. LOFSTROM.
